US0D1100229S

(12) **United States Design Patent** (10) **Patent No.:** **US D1,100,229 S**
(45) **Date of Patent:** **** Oct. 28, 2025**

(54) **THERMOTHERAPY DEVICE**

(71) Applicant: **CERAGEM CO., LTD.**,
Chungcheongnam-do (KR)

(72) Inventors: **Hyojin Kim**, Gyeonggi-do (KR);
Jongoh Lee, Gyeonggi-do (KR);
Junghyun Jo, Gyeonggi-do (KR)

(73) Assignee: **CERAGEM CO., LTD.**,
Chungcheongnam-Do (KR)

(**) Term: **15 Years**

(21) Appl. No.: **29/946,712**

(22) Filed: **Jun. 11, 2024**

(30) **Foreign Application Priority Data**

Dec. 13, 2023 (KR) 30-2023-0050954

(57) **CLAIM**

The ornamental design for a thermotherapy device, as shown and described.

DESCRIPTION

FIG. 1 is a perspective view of the thermotherapy device, showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the thermotherapy device that form no part of the claimed design.

1 Claim, 7 Drawing Sheets
